S. A. Whitney

S. A. WHITNEY, OF GLASBOROUGH, NEW JERSEY.

Design No. 3,428, dated March 23, 1869.

DESIGN FOR THE BODY OF A PICKLE-JAR.

The Schedule referred to in these Letters Patent and making part of the same.

To all whom it may concern:

Be it known that I, S. A. WHITNEY, of Glasborough, county of Gloucester, State of New Jersey, have originated a new Design for the Body of a Pickle-Jar; and I do hereby declare that the accompanying drawing, and following explanation thereof, form a full, clear, and exact description of the said design.

In the drawing—

Figure 1 represents a perspective view of my design for the body of a pickle-jar, and

Figure 2, a sectional plan of the same.

Viewed as shown in fig. 2, the body of the jar has four concave sides, arranged as illustrated, the corners, *e*, being fluted from the top to the base of the body.

As shown on fig. 1, the jar is largest at the point *a*, and tapers gradually to the base, *b*, in one direction, and to the top, *d*, of the body, in the opposite direction.

I claim the design for the body of a pickle-jar, substantially as described, and illustrated in and by the accompanying drawing.

In testimony whereof, I have signed my name to this specification, in the presence of two subscribing witnesses.

S. A. WHITNEY.

Witnesses:

JOHN WHITE,
HARRY SMITH.
